(57) **CLAIM**

The ornamental design for a platform for inversion device, as shown and described herein.

DESCRIPTION

FIG. 1 is a front perspective view of a platform for inversion device showing our new design;

FIG. 2 is a front view thereof;

FIG. 3 is a rear view thereof;

FIG. 4 is a first side view thereof;

FIG. 5 is a second side view thereof;

FIG. 6 is a top view thereof;

FIG. 7 is a bottom view thereof; and,

FIG. 8 is a front perspective view of an inversion device with the platform for inversion device operatively connected thereto.

The broken lines in FIG. 8 depict environmental subject matter and form no part of the claimed design.
